(57) **CLAIM**

The ornamental design for an outlet bank, as shown and described.

DESCRIPTION

FIG. 1 is a perspective view of an embodiment of an outlet bank.

FIG. 2 is a front elevation view thereof.

FIG. 3 is a back elevation view thereof.

FIG. 4 is a right side elevation view thereof.

FIG. 5 is a left side elevation view thereof.

FIG. 6 is a top plan view thereof.

FIG. 7 is a bottom plan view thereof.

FIG. 8 is a perspective view of an embodiment of an outlet bank.

FIG. 9 is a front elevation view thereof.

FIG. 10 is a back elevation view thereof.

FIG. 11 is a right side elevation view thereof.

FIG. 12 is a left side elevation view thereof.

FIG. 13 is a top plan view thereof; and,

FIG. 14 is a bottom plan view thereof.

Any broken lines in the Figures are for the purpose of illustrating environment only and form no part of the claimed design.

In the drawings, the broken lines are for the purpose of illustrating environment only and form no part of the claimed design.

1 Claim, 10 Drawing Sheets
